UNITED STATES PATENT OFFICE

THOMAS ELLIOTT, OF BIRMINGHAM, ALABAMA, ASSIGNOR, BY MESNE ASSIGNMENTS,
TO THE CINCINNATI CAR CORPORATION, OF WINTON PLACE, OHIO, A CORPORA-
TION OF OHIO

RAILWAY CAR

Original application filed December 9, 1925, Serial No. 74,324. Divided and this application filed August 5, 1926. Serial No. 127,451.

This invention relates to improvements in structural frames for use in building railway car bodies, particularly interurban and city railway cars, although the invention is applicable to the construction of motor buses and horse-drawn vehicles such as omnibuses and passenger transfer conveyances commonly known as depot wagons.

More particularly this invention constitutes an improvement in or addition to the structural frame set forth and claimed in my application filed November 3, 1925, Serial No. 66,633, and assigned to my present assignee, The Cincinnati Car Company.

15 The essential features of the present invention consist of a structural frame of the character set forth in my other application improved by the provision of a series of ventilating openings in one bar or member of such 20 frame, which openings lead from the outside to the inside of the car, and an open-work slide or damper placed across such openings in the frame bar and adapted by adjustment to more or less open and shut the ventilating 25 openings according as a passenger may desire.

A further feature of this invention consists of certain bell crank push buttons by which the passenger may adjust the slide with respect to the openings in the frame, and of 30 springs which act to hold the slide in any adjusted position.

In the accompanying drawings:

Figure 1 is an enlarged detail elevation looking at the inner side of one wall of a car 35 with my ventilating devices mounted therein;

Figure 2 is an enlarged detail view of a part of the structural frame and a part of the sash with my ventilating improvements shown on an enlarged scale;

40 Figure 3 is a longitudinal sectional view on the line 3—3 of Figure 2, showing the parts partly in section and partly in plan;

Figure 4 is a longitudinal sectional view of the ventilator slide on an enlarged scale;

45 Figure 5 is a side elevation of such slide;

Figure 6 is a longitudinal sectional view through the front plate; and

Figure 7 is a side elevation of such plate.

Referring to Figure 1, an interior view 50 looking toward one side of the car, it will be

seen that there is a succession of structural frames indicated at 1. These frames extend from that part of the car body which commences at the side sill and extends to the belt rail, and they extend thence upward to the 55 roof structure or that part thereof which constitutes the panel where the letter-board is located. All of this is set forth fully in the application of Thomas Elliott referred to above. In this present case these structural 60 frames are provided with openings 2 in the outer wall of the lower member or bar and a general opening 3 in the inner wall. The openings 2 are opened and closed by a sliding damper 4 in the nature of a plate having a 65 succession of openings 5 corresponding in size and position with the openings 2 in the structural frame, as clearly seen in Figure 3. This damper slide is fitted to rest on the interior of the lower bar of the structural frame as 70 indicated generally in Figure 3. It is held in place against the frame by coil springs 7 clearly shown in Figure 3. These springs are mounted on bell crank push buttons 8 and bear at one end on the shoulder 9 and at the 75 other end against a washer 10 which in turn is to be pressed against the cross pin 11 carried by the sliding damper 4. In this way the damper is properly held against the wall of the structural frame in any position to which it may be adjusted by pushing inward on one or the other of the push button surfaces 12 of the push button levers. For instance, when the ventilating damper is in the position shown in Figure 3 the springs are exerting a 80 pressure against it in a direction to the right of the pivots of the bell crank levers, while if the damper is adjusted to the other extreme position these springs will be exerting their pressure in a line at the left of their pivots. 85 Again, if the damper is adjusted, say half way across the ventilating openings 2, the springs will exert their pressure directly against the damper and by the friction thus created between the damper and the wall of the structural frame, will hold the damper in such position.

The numeral 13 refers to a front plate secured as by screws 14 to the inner face of the structural frame. This plate has ventilating 100

openings 15 so that whatever air is let in through the openings 2 in the structural frame and through the damper will enter the car.

5 The sash actuating mechanism comprises a shaft 21 rotatably mounted in the plate 13, the plate 13 serving as a bearing for the shaft. Mounted upon the shaft is an eccentric 19, carrying the arms 17 and 17^a, these arms terminating in projections 18 and 18^a respectively, which projections engage the rack bar 16, secured to the frame for operating the window sash. The shaft and arms are operated by means of a crank 20 provided with a handle 20^a, the crank 20 being secured to the shaft 21 at the point 22. It will thus be seen that by rotating the shaft 21, either arm 17 or 17^a may be brought into engagement with the rack bar to open or close the window as desired. These features are more fully set forth in my copending application, Serial 74,324, filed December 9, 1925, of which this present application is a division.

Thus it will be understood that I have provided a practical means by which limited quantities of the outer air may be admitted into the car for purposes of ventilation.

Again, the ventilating damper may be opened without moving the window sash.

30 It will be understood that I desire to comprehend within my invention such modifications as may be necessary to adapt it to varying conditions and uses.

Having thus fully described my invention, 35 what I claim as new and desire to secure by Letters Patent, is:

1. The combination with a car structural frame having ventilating openings in one of the bars thereof; of a damper mounted within 40 the frame adjacent said openings, and an actuating means for the damper comprising bell crank levers and springs.

2. The combination with a car structural frame having ventilating openings, of a 45 damper mounted adjacent said openings and bell crank levers operable by hand, and having springs which exert a pressure against the damper, whereby when the levers are actuated the damper is adjusted and whereby through 50 the action of the springs the damper is held in any adjusted position.

3. The combination with a car structural frame having a hollow bar and ventilating 55 openings in the outer wall; of a damper mounted within the bar and slidably across said openings, and bell crank levers mounted in the bar, connected at one end to the damper and hand-operable at the other end.

4. The combination with a car structural 60 frame having a hollow bar and ventilating openings in the outer wall, of a damper mounted within the bar and slidably across 65 said openings, bell crank levers mounted in the bar, connected at one end to the damper and hand-operable at the other end, and a coil

spring mounted on each lever and arranged to exert pressure against the damper to hold it in any adjusted position.

5. The combination with a car structural frame, having ventilating openings through 70 which air may be admitted into the car, of a non-pivoted damper to control said openings, means to adjust the damper in one direction and a second means to adjust said damper in the other direction, said damper, and the 75 means to adjust it, being mounted in said frame.

6. The combination with a car structural frame, having ventilating openings to admit air into the interior of the car, of a non-pivoted damper mounted in said frame to control the admission and exclusion of the air, push button means mounted in the frame to adjust said damper in one direction and a second push button means to adjust the 85 damper in another direction.

In testimony whereof, I affix my signature.

THOMAS ELLIOTT.
